(57) **CLAIM**

We claim the ornamental design for a control panel for an
appliance, as shown and described.

DESCRIPTION

FIG. 1 is a front elevational view of a control panel for an
appliance of the present disclosure;

FIG. 2 is a front perspective view of the control panel of
FIG. 1;

FIG. 3 is a front elevational view of area V of the control
panel of FIG. 1;

FIG. 4 is a front elevational view of a control panel for an
appliance of the present disclosure;

FIG. 5 is a front perspective view of the control panel of
FIG. 4;

FIG. 6 is a front elevational view of area VIII of the control
panel of FIG. 4;

FIG. 7 is a front elevational view of a control panel for an
appliance of the present disclosure;

FIG. 8 is a front perspective view of the control panel of
FIG. 7;

FIG. 9 is a front elevational view of area XI of the control
panel of FIG. 7;

FIG. 10 is a front elevational view of a control panel for an
appliance of the present disclosure;

FIG. 11 is a front perspective view of the control panel of
FIG. 10;

FIG. 12 is a front elevational view of area XIV of the control
panel of FIG. 10;

FIG. 13 is a front elevational view of a control panel for an
appliance of the present disclosure;

FIG. 14 is a front perspective view of the control panel of
FIG. 13;

FIG. 15 is a front elevational view of area XVII of the
control panel of FIG. 13;

FIG. 16 is a front elevational view of a control panel for an
appliance of the present disclosure;

FIG. 17 is a front perspective view of the control panel of
FIG. 16; and,

FIG. 18 is a front elevational view of area XX of the control
panel of FIG. 16.

The broken lines depict portions of the article that form no
part of the claimed design.
